SPRAY NOZZLE

John Mayer, Hastings, Minn., assignor to H. D. Hudson Manufacturing Company, Chicago, Ill., a corporation of Minnesota

Application December 4, 1937, Serial No. 178,102

3 Claims. (Cl. 251—165)

This invention relates to new and useful improvements in spray nozzles and more particularly to the valve operating means thereof.

An object of the present invention is to provide

5 a spray nozzle comprising a valve having a suitable operating handle, and means being provided in connection with said handle for holding the valve in open position.

10 A further object is to provide a valve mechanism for controlling fluid flow from a suitable conduit, and said valve mechanism comprising an operating handle having a trigger element associated therewith and adapted to automatically assume a position to hold the valve in open position, when the handle is operated to open the valve mechanism, said trigger element being so arranged that it may be conveniently moved into inoperative position by the operator's finger, when it is desired to close the valve.

15 20 Features of the invention reside in the unique construction of the means for holding the valve in open position; in the novel mounting of said means, which comprises a pivoted element having a small lever positioned in a manner similar to the trigger on a gun, whereby it may be conveniently moved from one position to another, by the operator's forefinger, when the valve is in use.

25 Other objects of the invention will appear from the following description and accompanying drawing and will be pointed out in the annexed claims.

30 In the accompanying drawing there has been disclosed a structure designed to carry out the various objects of the invention, but it is to be understood that the invention is not confined to the exact features shown as various changes may be made within the scope of the claims which follow.

35 40 In the drawing:

Figure 1 is a view partially in section, showing the trigger element embodied in the construction of a conventional spray nozzle, and the trigger element being shown in valve opening position;

45 Figure 2 is an exterior view of the spray nozzle showing the element in inoperative or valve closing position; and

Figure 3 is a view showing a valve holding element of slightly different construction.

50 55 In the selected embodiment of the invention here shown, there is illustrated, for purposes of disclosure, a spray nozzle comprising a hollow body 2 having a threaded socket 3, whereby it may be conveniently attached to one end of a suitable pipe 4, leading to a source of liquid or

fluid under pressure. The body 2 is shown provided at its opposite end with a threaded extension 5 adapted to receive a conventional spray head 6, indicated in dotted lines in Figure 1.

As best illustrated in Figure 1, the body 2 is provided internally with a valve seat 7, adapted to be engaged by a suitable valve 8, whereby fluid flow through the passage 9, connecting the interior of the valve body with the spray head 6, may be controlled. The valve 8 is shown having a stem 11, the lower end of which is guidingly supported in a cap 12, received in threaded engagement with the body 2 of the nozzle, as shown at 13 in Figure 1. A suitable packing 14 is preferably provided in the cap 12, and is held in position by the action of a spring 15. This spring also serves to constantly urge the valve 8 into engagement with the seat 7.

The projecting end portion 16 of the valve stem 11 is shown pivotally connected to an operating handle 17, which in turn, is pivoted to the body 2, as shown at 18. The handle 17, being pivotally connected to the valve stem 11, is normally held in the position shown in Figure 2 by the action of the spring 15.

20 25 An important feature of the present invention resides in the provision of means for holding the valve in open position, without grasping the handle 17 and depressing it. As clearly illustrated in the drawing, the means for thus holding the valve in open position is shown comprising an element, generally indicated by the numeral 19. This element is pivotally connected to the pivot pin 21, which connects the valve stem to the handle 17. The pivotal connections 18 and 21 are sufficiently loose to permit the lever 19 and valve stem 11 to move freely without binding, when the lever is actuated.

30 35 The element 19 is preferably made of sheet metal, and comprises a U-shaped body which straddles or fits over a portion of the handle 17, whereby the pivot pin 21 may be inserted through the aligned apertures provided in the side walls 22 of the element 19, handle 17, and terminal 16 of the valve stem 11.

40 45 The wall portions 22 of the pivoted element 19 are eccentrically disposed with respect to the axis of the pivot pin 21, whereby when the element is positioned as shown in Figure 1, the upper edges of its wall portions 22 will engage the adjacent face of the cap 12 and thereby hold the valve 8 in open position, as clearly illustrated in Figure 1.

50 55 The element 19 has a finger engaging portion 23, simulating somewhat a trigger. It is adapted to be engaged by the forefinger of the operator's

hand, whereby it may be conveniently moved from the position shown in Figure 1, to that shown in Figure 2, or, in other words, from operative to inoperative position. A spring 24 is shown 5 having one end connected to a small arm or extension 25 of the element 19, and its opposite end is suitably secured to the handle 17, as shown at 26 in Figure 1. The spring 24 constantly urges the element 19 into operative position, as shown 10 in Figure 1, thereby to hold the valve in open position. When the element 19 is swung into the position shown in Figure 2, the valve may move into engagement with the seat 7 to prevent or control fluid flow through the body 2.

15 In the operation of the apparatus, the operator may grasp the pipe 4, one end of which is usually connected to a flexible hose having a connection with a source of liquid under pressure. The handle 17 is conveniently located 20 adjacent to the pipe 4 so that the operator may, if he so desires, grasp both the pipe 4 and handle 17 with one hand, during the spraying operation. When the handle 17 is moved to valve 25 opening position, as shown in Figure 1, the pivoted element 19 comes into play, and unless the operator holds it in the position shown in Figure 2, automatically assumes the position shown in 30 Figure 1, thereby holding the valve in open position so that the operator may release his grip 35 upon the handle 17. The spray nozzle and head may then be moved about in any convenient manner without requiring any attention on the part of the operator. This enables the operator to hold the spray nozzle in any desired position, 40 when spraying shrubbery, trees, and other plants, and greatly facilitates the operation of spraying in that the spray nozzle or head may be conveniently held in an inverted position under the leaves of the plants without twisting or bending 45 the wrists and arms, as is often necessary, when the valve handle 17 must be manually held in open position.

When the valve is to be closed, the operator simply moves his forefinger into engagement with 45 the trigger 23 and pulls it downwardly from the position shown in Figure 1 to that shown in Figure 2, whereupon the spring 15 will cause the handle 17 to move into valve closing position, as shown in Figure 2.

50 From the foregoing, it will be noted that the pivoted trigger element provides a very simple and practical device for holding the valve in open position. In ordinary use, particularly when the operator finds it necessary to constantly alternately open and close the valve 8, the operator may keep his forefinger on the trigger 23 and hold it in the position shown in Figure 2, whereby it is ineffective to hold the valve open. When, however, the operator finds it desirable 55 to lock the valve in open position, he simply releases the trigger 23 and opens the valve by inwardly pressing the handle 17 toward the pipe 4, whereupon the spring 24 will automatically swing the trigger element 19 into operative position, as shown in Figure 1, in which position it 60 will be held by the spring 24 until the operator again swings it into inoperative position by depressing the trigger 23.

The invention herein disclosed, has proven very practical and efficient in operation and presents the utmost in simplicity. Its construction is such that it may readily be attached to spray nozzles of the general character illustrated in the drawing, substantially without requiring any alterations in the construction thereof. It is to be noted that the element 19 is supported entirely by the pivot pin 21, which connects the upper end of the handle 17 to the valve stem 16, 10 whereby it may readily be detached from the spray head, when desired.

In Figure 3, there is shown a structure of slightly different construction, in which a manually operable element, generally indicated by the 15 numeral 27, is utilized for holding the valve 8 in open position. In the form here shown, the element 27 comprises a body portion 28 of box-like formation, which is pivoted to the stem 16 and handle 17, in a manner similar to the form 20 shown in Figures 1 and 2. The body portion 28 is provided with suitable finger-engaging portions 29 which are so disposed that they may be conveniently manipulated by the operator's finger to move the element 27 from one position to 25 the other, as indicated by the full and dotted lines in Figure 3. The finger-engaging portion 29 of the element 27 may be otherwise formed, as will readily be understood, provided it is so arranged that it may be conveniently engaged 30 by the operator's finger to move the element into or out of valve-opening position.

I claim as my invention:

1. In a device of the class described, a body having a passage therein provided with a valve 35 seat, a valve normally closing said seat and having a stem protruding from the body, a valve operating handle pivotally supported on said body and having a pivot connecting it to the valve stem, and a trigger device supported on said pivot and having an eccentrically disposed portion adapted to be moved into engagement with the valve body, when the valve is open, thereby to hold the valve open.

2. In a spray nozzle, a hollow body having 45 means for connecting it to a source of liquid under pressure, a valve seat within the body, a valve normally closing said seat and having a stem projecting from the body, an operating handle for the valve, an element for holding the 50 valve in open position, and a single pivot pin for operatively connecting together the valve stem, operating handle and said element.

3. In a spray nozzle, a hollow body having 55 means for connecting it to a source of liquid under pressure, a valve seat within the body, a valve normally closing said seat and having a stem projecting from the body, an operating handle for the valve, an element for holding the 60 valve in open position, and a single pivot pin for operatively connecting together the valve stem, operating handle and said element, said element comprising a U-shaped body which embraces a portion of the handle and said valve stem, thereby to equalize the strain imparted to 65 said parts.

JOHN MAYER.
